PRODUCTION OF SUBSTANTIALLY ODORLESS
ALKYL ARYL SULFONATE DETERGENTS

Richard Dale Stayner, Berkeley, Calif., assignor to California Research Corporation, San Francisco, Calif., a corporation of Delaware

No Drawing. Application July 2, 1952,

Serial No. 296,930

3 Claims. (Cl. 260—505)

This invention relates to a process for producing substantially odorless alkyl aryl sulfonate detergents and to an alkyl aryl hydrocarbon composition convertible to substantially odorless sulfonate detergent by conventional processing methods.

Synthetic detergents are currently produced and consumed in very large quantities. The great bulk of synthetic detergents now manufactured and sold are alkyl aryl sulfonate detergents prepared by reacting an alkyl benzene containing 10 to 18 carbon atoms in the alkyl group with concentrated sulfuric acid and neutralizing the sulfonic acids thus produced. The alkyl benzenes employed as raw materials are, for the most part, polypropylene benzenes prepared by alkylating benzene with a propylene polymer fraction containing from 10 to 18 carbon atoms in the polymer chains, and keryl benzenes prepared by chlorinating kerosene and condensing the resulting alkyl chloride with benzene.

It has been observed that upon completion of the sulfonation and neutralization steps the detergents, especially if produced from a branched-chain alkyl benzene, may have a rather unpleasant odor of the character of neutralized petroleum sludge. In sulfuric acid treatment of petroleum fractions this odor is often encountered in the neutralized acid sludge. When the alkyl aryl sulfonate detergent is blended with builders to produce a final detergent composition containing from 15 to 25% of active detergent material, the odor level is reduced, but is still sufficiently high to give rise to consumer complaints.

Actually, two types of odor difficulty have been experienced with alkyl aryl sulfonate detergents: neutralized sludge type odor, which emanates from the detergent material immediately upon completion of the sulfonation and neutralization steps; and a rancid odor which develops on storage. The development of rancidity on storage appears to be more characteristic of the keryl benzene detergents than of the polypropylene benzene type detergents. With the former, rancidity develops rapidly upon storage at fairly high temperature, while the latter develops a rancid odor only infrequently and then following long storage at high temperature in the presence of very appreciable quantities of moisture. The rancid odor developed on storage is discussed in U. S. Patent No. 2,469,376, which teaches that the development of such an odor may be prevented by the addition of an amino aromatic compound to the neutralized detergent slurry before it is dried.

The present invention is not concerned with the rancid odor which is developed on storage, but rather with the neutralized sludge odor which is characteristic of the freshly prepared detergent. It has now been found that a substantially odorless alkyl aryl sulfonate detergent may be produced by sulfonating a branched-chain alkyl benzene in the presence of from 0.02 to 0.1% by weight of ortho-phenylenediamine, para-phenylenediamine, or mixtures of ortho- and para-phenylenediamine, based on the alkyl benzene hydrocarbon material.

The invention may be better understood from the following examples:

Example 1

A polypropylene benzene hydrocarbon of the type described in U. S. Patent No. 2,477,382 and boiling in the range from 500° F. to 625° F. was sulfonated with 20% fuming sulfuric acid. The sulfuric acid was added to the hydrocarbon with constant stirring over a period of about one hour. 3 mols of sulfuric acid were added for each mol of hydrocarbon present. Upon completion of the addition of acid, the acid-hydrocarbon mixture was digested at a temperature from 85° F. to 105° F. for two hours, during which period the sulfonation reaction was completed. Water was added to the reaction mixture in amount sufficient to reduce the concentration of the unreacted sulfuric acid to 80% by weight. The diluted reaction mixture was settled for a period of two hours at 140° F. An upper organic layer consisting predominantly of alkyl benzene sulfonic acids and a lower aqueous layer consisting predominantly of aqueous sulfuric acid were formed. The layers were separated and the alkyl benzene sulfonic acid layer was neutralized with sodium hydroxide. In this example and in the following examples, ammonium hydroxide, potassium hydroxide or magnesium hydroxide may be used to neutralize the sulfonic acid layer without any effect on the observed odor character of the product. An aqueous solution of the neutral product having a sodium alkyl benzene sulfonate content of 10% by weight was tested for odor immediately and found to have a strong odor of the type generally characteristic of neutralized sludge. A portion of the neutral product was drum-dried and was observed to have a strong sludge odor.

Example 2

The process described in Example 1 was repeated. Before adding the acid to the alkyl benzene hydrocarbon, 0.001% by weight of para-phenylenediamine was dissolved in the alkyl aryl hydrocarbon. Both the 10% aqueous solution of the neutral product and the dry neutral product still exhibited a strong sludge odor.

Example 3

Example 1 was repeated. 0.01% by weight of para-phenylenediamine was dissolved in the alkyl benzene hydrocarbon prior to addition of the sulfuric acid. The odor of a 10% aqueous solution of the neutral product produced was substantially less intense than the odor of the 10% solution produced in Example 1 and was of the same general character. The odor of the dry neutral product was similarly reduced in intensity.

Example 4

Example 1 was repeated. 0.022% by weight of para-phenylenediamine was dissolved in the alkyl benzene hydrocarbon prior to the addition of the acid. A 10% solution of the neutral product had a very mild odor, the sludge character being barely perceptible.

Example 5

Example 1 was repeated. Immediately after the addition of the acid to the alkyl benzene hydrocarbon and before the two-hour digestion period, para-phenylenediamine amounting to 0.05% by weight based on the alkyl benzene hydrocarbon was added to the mixture. A 10% solution of the neutral product was essentially odorless. The dry neutral product was also essentially odorless.

Example 6

Example 5 was repeated, substituting ortho-phenylenediamine for para-phenylenediamine. A 10% solution of the neutral product was essentially odorless. The dry neutral product was also essentially odorless.

Example 7

Example 5 was repeated, substituting a mixture of equal parts by weight of ortho-phenylenediamine and para-phenylenediamine for the para-phenylenediamine of Example 5. A 10% solution of the neutral product was essentially odorless. The dry neutral product was also essentially odorless.

Example 8

Example 1 was repeated. 0.1% by weight of para-phenylenediamine was suspended in the alkyl benzene hydrocarbon prior to the addition of the acid. A 10% solution of the neutral product was essentially odorless.

Example 9

Example 1 was repeated omitting the water dilution and acid-settling steps. 0.05% by weight of para-phenylenediamine was dispersed in the alkyl benzene hydrocarbon prior to the addition of the acid. The sulfonation reaction product was neutralized immediately upon completion of the sulfonation reaction. The dry neutral product had a very mild odor, but had a definite gray color indicating that the water dilution and acid-settling steps should be taken if a pure white product is desired.

Ortho- or para-phenylenediamine is similarly effective in reducing the odor level of the fresh sodium alkyl benzene sulfonate obtained from keryl benzenes containing 10 to 18 carbon atoms in the alkyl group.

The action of ortho- or para-phenylenediamine in reducing the odor level of freshly prepared sodium alkyl benzene sulfonates is specific. Other amino aromatic compounds are not effective. When Example 6 is repeated using meta-phenylenediamine, the odor of the neutral product is practically indistinguishable from the odor of the product in Example 1.

Ortho- or para-phenylenediamine obviously acts to inhibit the formation of those side reaction products during the sulfonation step which impart the undesirable odor to the finished detergent. The manner in which ortho- or para-phenylenediamine accomplishes this result is not understood. An intermediate compound of ortho- or para-phenylenediamine and sulfuric acid may be formed. It is observed that when ortho- or para-phenylenediamine is added to the sulfuric acid alone, a purple color immediately develops, indicating reaction of some sort. However the ortho- or para-phenylenediamine may function to accomplish the result indicated above, it appears that no ortho- or para-phenylenediamine is present as such in the final detergent product. Further, if the water dilution and acid-settling steps are employed, the final detergent product also appears to be free of any derivative of ortho- or para-phenylenediamine. Due to the known skin sensitization reaction of para-phenylenediamine, it is desirable to practice acid dilution or to employ some other means of reducing the amount of para-phenylenediamine or its reaction products to a minimum. The use of ortho- or para-phenylenediamine in the manner above described is effective only to inhibit the development of the neutralized acid sludge odor in the freshly prepared detergent. If the neutral detergent product is stored at high temperature in the presence of an appreciable amount of moisture for a long period of time, a rancid odor quite different from the odor of the freshly prepared detergent can be developed. As a practical matter the development of rancidity is not a problem with alkyl aryl sulfonate detergents prepared from polypropylene benzene. If it is desired to prepare a detergent from the keryl benzene which is odorless immediately after preparation, and which does not develop a rancid odor upon storage, the sulfonation should be conducted in the presence of ortho- or para-phenylenediamine in the manner described, and a small amount of hydroquinone, usually from 0.001 to 0.005% by weight based on the sodium alkyl benzene sulfonate should be added to the neutral product before drying it.

As indicated in the examples, ortho- or para-phenylenediamine, to be effective in suppressing the development of the neutralized sludge type odor in the freshly prepared detergent, must be present while the sulfonation reaction is going on. It may be added to the alkyl benzene hydrocarbon prior to mixing the hydrocarbon and acid, or it may be added very shortly after mixing the hydrocarbon and acid while the sulfonation reaction is under way. If the ortho- or para-phenylenediamine is not added until the sulfonation reaction is essentially completed, it is ineffective.

At least 0.01% by weight of ortho- or para-phenylenediamine should be added to the alkyl benzene if any appreciable odor improvement is to be achieved. Preferably, the amount of ortho- or para-phenylenediamine added is in the range from 0.02 to 0.1% based on the alkyl benzene hydrocarbon.

Ortho- and para-phenylenediamine are only sparingly soluble in alkyl benzenes having 10 to 18 carbon atoms in the alkyl chain. At room temperature a saturated solution contains about 0.025% by weight. This quantity is sufficient to effect a marked improvement in the odor of the fresh detergent prepared by sulfonation and neutralization. A substantially saturated solution of ortho- or para-phenylenediamine in the alkyl benzene constitutes an excellent raw material from which to produce alkyl aryl sulfonate detergents of good odor. Such solutions can be conveniently prepared by the manufacturer of the alkyl benzene hydrocarbon and shipped to detergent manufacturers who may directly sulfonate the solution, neutralize the resultant sulfonic acid, add the desired builders, and dry the product.

The solubility of ortho- or para-phenylenediamine can be increased without impairing its effectiveness either by introducing an alkyl group into the nucleus to replace a nuclear hydrogen atom, or by replacing one of the amino hydrogens with an alkyl group.

I claim:

1. In a process for producing an alkyl aryl sulfonate detergent by sulfonating an alkyl benzene hydrocarbon having 10 to 18 carbon atoms in the alkyl group with concentrated sulfuric acid, settling the sulfonation reaction product to separate a sulfonic acid layer and an unreacted sulfuric acid layer, neutralizing the sulfonic acid layer and drying the neutral product, the improvement which comprises dispersing from 0.02 to 0.1% by weight of at least one aromatic amine of the group consisting of ortho-phenylenediamine and para-phenylenediamine in the hydrocarbon before the sulfonation reaction is complete.
2. A process for producing an alkyl aryl sulfonate detergent which comprises sulfonating an alkyl aryl hydrocarbon having 10 to 18 carbon atoms in the alkyl group with concentrated sulfuric acid in the presence of 0.02 to 0.01% by weight of at least one aromatic amine of the group consisting of ortho-phenylenediamine and para-phenylenediamine based on the hydrocarbon, diluting the reaction product mixture with water, settling the diluted mixture to separate an upper organic phase comprising sulfonic acids and essentially free of ortho- and para-phenylenediamine and a lower aqueous layer and neutralizing the upper layer with a base.
3. A composition suitable for sulfonation to produce a sulfonation product free of sludge odor, comprising an alkyl benzene hydrocarbon having 10 to 18 carbon atoms in the alkyl group in which is incorporated 0.01 to 0.1% by weight of at least one aromatic amine of the group consisting of ortho-phenylenediamine and para-phenylenediamine.
